United States Patent Office.

JOHN ROBSON, OF CHICAGO, ILLINOIS.

Letters Patent No. 95,380, dated September 28, 1869.

IMPROVEMENT IN NEWSPAPER-FILES.

The Schedule referred to in these Letters Patent and making part of the same.

To all whom it may concern:

Be it known that I, JOHN ROBSON, of the city of Chicago, in the State of Illinois, have invented certain new and useful Improvements in Newspaper-Files; and I do hereby declare that the following is a full, clear, and exact description thereof, reference being had to the accompanying drawings, making part of this specification, in which—

Figures 1 and 3 are elevations, showing opposite sides.

Figure 2, a transverse, and

Figure 4, a longitudinal section.

Figure 5, a longitudinal, and

Figure 6, a transverse section, showing a modification in the construction of the file.

To enable those skilled in the art to make and use my improvements, I proceed to describe the same.

A represents a bar, or piece of wood, provided with the usual handle at one end, while the inner side has a central longitudinal groove, to receive the rod B.

This rod is curved a little at the upper end, as shown in fig. 2, bringing such end just out of the groove in A, to facilitate the lateral movement of the rod.

This rod B is connected at a to the short pivot b, by a joint, and the pivot b passes through A, and moves loosely therein.

s is a spring, one end of which is fastened to A, while b passes through the other end.

When in proper place, the head c is secured upon b.

A slot, e, is provided in A, in the usual manner, and upon the lower end of B is any suitable device, d, for holding the rod D in its place at the lower end.

This newspaper-file will be found convenient for general use, and is especially adapted to hotels, libraries, reading-rooms, and other places where it is customary to remove and replace papers daily or frequently.

The distinguishing feature of my file is that the rod B is pivoted at its upper end to A, so that it can be moved laterally, in which respect it differs from all others, rendering it far more convenient to remove papers from and put them on the file, as the rod B can be swung or turned around laterally out of the way, while in all other files it can only be lifted up.

As described, the rod is susceptible of two movements, an upward and a lateral.

The spring s will hold the upper end of the rod down, keeping the papers in place, while the file may be so constructed that the rod will be rather tight at the lower end, as the rod will yield enough for ordinary uses. If necessary, a spring may be placed at the lower end, similar to s.

I accomplish the same object in a somewhat different manner, as shown in figs. 5 and 6, in which B' represents a strip of wood, taking the place of B, while A has no groove.

The pivot b passes through both bars A and B', both moving loosely on the pivot.

When so constructed, B' has the same lateral movement before described, and is susceptible of a limited upward movement. It can be raised up until the spring s comes in contact with A, and then it can be moved laterally as before.

Having thus fully described my invention,

What I claim as new, and desire to secure by Letters Patent, is as follows:

The combination and arrangement of the bar A, the rod or bar B, with the pivotal sliding bolt b, spring s, and fastening d, substantially as and for the purposes specified.

JOHN ROBSON.
